CLAMP ATTACHMENT FOR PLIERS

Alton Hudnall, Denver, Colo.

Application March 28, 1952, Serial No. 279,063

1 Claim. (Cl. 81—49)

1

This invention relates to improvements in clamp attachments for pliers and has reference more particularly to an attachment by means of which an ordinary pair of pliers may be converted into a hand vise thereby greatly increasing the usefulness of the pliers.

There are in the hands of the public today very large numbers of pliers of various kinds many of which have been part of tool kits furnished with automobiles.

It is the object of this invention to produce a simple attachment that can be carried in the tool box or kept on the work bench and which can quickly and easily be applied to the handles of an ordinary pair of pliers for holding an article clamped in its jaws while the article is worked on for other purposes.

Another object is to produce an attachment that requires no change in the construction of the pliers, which is easily applied and removed and which will not become accidentally removed when in use.

In order to describe the invention so that its construction and mode of operation can be readily understood reference will now be had to the accompanying drawing in which the invention has been illustrated and in which

Figure 1 is a side elevational view of an ordinary pair of pliers showing the attachment in place thereon;

Figure 2 an end view showing the relationship of the clamp device to the handles of the pliers;

Figure 3 is a view showing a modification of the embodiment shown in Figure 2, the lower or movable member being shown in section;

Figure 4 is a diagram showing a slightly modified form.

Referring now to the drawing numerals 5 and 6 designate respectively the upper and the lower handles of a pair of pliers. The pliers shown is of a common and well known construction and is merely representative of pliers as a class and will therefore not be described in detail. The handles terminate in jaws 5a and 6a and move relative to each other about pivot 7. A nut 8 is shown clamped between the plier jaws.

The attachment consists of a bolt 9 having its upper end turned to one side as indicated by reference numeral 10 and is provided with an opening 11 of the proper shape and size to receive the handle 5 of the plier.

A plier handle grip 12 is slidably attached to the bolt as shown most clearly in Figure 3 and is held in place therein by a wing nut 13. Member 12 has an opening 14 the same size and shape

2

as opening 11 in part 10 and is also provided with an opening 15 through which the bolt extrudes. The axis of openings 14 and 15 are at right angles to each other.

The handles of practically all pliers are of oval or oblong cross section and are practically never circular and holes 11 and 14 are therefore of somewhat similar shape.

Let us now assume that the clamp attachment 10 is in position on the plier as shown in Figure 1 and the nut 13 turned so as to put the bolt under tension.

From Figure 3 it will be seen that the hole in handle grip 12 through which the bolt passes is somewhat larger than the bolt so that it may tilt thereon. Hole 14 through which handle 6 passes should preferably fit the handle snugly. When the nut is turned to put the bolt under tension handle grip member 12 will tend to turn on on handle 6 and this will effect a binding action which causes it to grip the handle and thus prevent it from sliding along the handle. If end 10 were connected with the bolt by means of a pivot 16 as indicated in Figure 3 the torque produced would produce a gripping action similar to that described in connection with member 12. It has been found, however, that the gripping action of member 12 is sufficient to hold the attachment in place.

It is obvious that various modifications can be made without departing from the basic concept of the invention which in its broadest aspect comprises a bolt or other tension member 9 with two laterally extending plier handle gripping members corresponding to 10 and 12, one of which can be moved longitudinally by means of a nut, preferably a wing nut.

Attention is directed to the fact that the handle grips 10 and 12 extend laterally, as shown and described and that at least one can tilt relative to the bolt for this produces a gripping action on the handles and has other advantages that are apparent.

In Figure 4 a slightly modified form of the invention has been shown in which the plier handle grips 10 and 12 are identical and are slidably mounted on bolt 9 and separated by a helical compression spring 17. This embodiment is somewhat simpler than the others and is embraced in the claims.

It is also contemplated to provide the head of the bolt with wings and to provide plier handle grip 12 with threads in which case nut 13 may be dispensed with.

What is claimed as new is:

A clamp device for use with pliers having pivoted handles provided with opposing jaws at one end, said clamp device comprising, a bolt having one end provided with a laterally extending plier handle grip having an opening of the size and shape to receive a plier handle, a second laterally extending plier handle grip slideable on the bolt and tiltable relative thereto having a hole of the size and shape to receive the other plier handle, the bolt having a threaded section, and means in engagement with the threads on the bolt for moving the plier handle

grips towards each other when the means is turned relative to said bolt.

ALTON HUDNALL.
